[57] CLAIM

The ornamental design for a toggle anchor, as shown
and described.

DESCRIPTION

FIG. 1 is a perspective view of a first toggle anchor
showing our new design;

FIG. 2 is a top plan view thereof;

FIG. 3 is a front elevational view thereof, the rear eleva-
tional view thereof being identical;

FIG. 4 is a bottom plan view thereof;

FIG. 5 is a right side elevational view thereof, the left
side elevational view thereof being identical;

FIG. 6 is a perspective view of a second embodiment of
the design of FIG. 1;

FIG. 7 is a top plan view of FIG. 6;

FIG. 8 is a front elevational view of FIG. 6, the rear
elevational view thereof being identical;

FIG. 9 is a bottom plan view of FIG. 6; and,

FIG. 10 is a right side elevational view of FIG. 6, the
left side elevational view thereof being identical.
